RESINS CASTING MACHINE

Raymond W. Kerr, 3731 N. 58th St.,
Lincoln, Nebr. 68529

Filed Nov. 24, 1970, Ser. No. 26,144

Term of patent 14 years

Int. Cl. D15—99

U.S. Cl. D55—1

FIG. 1 is a perspective view of my new design for resins casting machine taken from the top, forward, and rightward directions;

FIG. 2 is a rear elevational view of my resins casting machine, the forward elevational view being a substantial mirror image thereof;

FIG. 3 is a left side elevational view thereof; and

FIG. 4 is a top plan view.

I claim:

The ornamental design for a resins casting machine, as shown in the accompanying drawing.
